(57) CLAIM

The ornamental design for a trailer with flatbed, as shown and described.

DESCRIPTION

FIG. 1 is a front right side perspective view of a trailer with flatbed showing my new design;

FIG. 2 is a back left side perspective view of the trailer with flatbed thereof;

FIG. 3 is a right side elevation view thereof;

FIG. 4 is a left side elevation view thereof;

FIG. 5 is a top plan view thereof;

FIG. 6 is a front elevational view thereof; and,

FIG. 7 is a rear elevational view thereof.

The broken lines illustrate portions of the trailer with flatbed that form no part of the claimed design.
